US00D751560S

(12) **United States Design Patent**
Akana et al.

(10) **Patent No.:** US D751,560 S
(45) **Date of Patent:** ** Mar. 15, 2016

(54) **ADAPTER**

(71) Applicant: **Apple Inc.**, Cupertino, CA (US)
(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/530,282**

(22) Filed: **Jun. 15, 2015**

Related U.S. Application Data

(63) Continuation of application No. 29/477,506, filed on Dec. 23, 2013, now Pat. No. Des. 732,035, which is a continuation of application No. 29/456,487, filed on May 31, 2013, now Pat. No. Des. 707,681, which is a continuation of application No. 29/431,556, filed on Sep. 7, 2012, now Pat. No. Des. 684,976.

(57) **CLAIM**

The ornamental design for an adapter, as shown and described.

DESCRIPTION

FIG. 1 is a top front perspective view of an adapter showing our new design;

FIG. 2 is a bottom rear perspective view thereof;

FIG. 3 is a front view thereof, the rear view being a mirror image thereof;

FIG. 4 is a side view thereof, the other side view being a mirror image thereof;

FIG. 5 is a bottom view thereof; and,

FIG. 6 is a top view thereof.

The dashed broken lines in the Figures show portions of the adapter that form no part of the claimed design.

The dot-dash broken lines in the Figures form no part of the claimed design.

The shade lines in the Figures show contour and not surface ornamentation.

1 Claim, 5 Drawing Sheets
